Primary Examiner—Carol Rademaker(74) *Attorney, Agent, or Firm*—Birch, Stewart, Kolasch & Birch, LLP(57) **CLAIM**

The ornamental design for a bottle, as shown and described.

DESCRIPTION

FIG. 1 is a front elevational view of a first embodiment of the bottle showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a front elevational view of a second embodiment of the bottle showing my new design;

FIG. 7 is a left side elevational view thereof;

FIG. 8 is a right side elevational view thereof;

FIG. 9 is a rear elevational view thereof;

FIG. 10 is a top plan view thereof; and,

FIG. 11 is a sectional perspective view through the bottom portion of the bottle sidewall thereof, showing the punt from the direction of FIG. 9, shown at an enlarged scale.

The stipple shading shown in the drawings represents a change in color, no particular color being specified.

For clarity, the overall pattern of slightly indented irregular shapes that would normally be seen through the transparent surface of the sidewall has not been shown.
